UNITED STATES PATENT OFFICE.

JAMES TALLEY, OF DENVER, COLORADO, ASSIGNOR TO SARAH E. TALLEY,
OF SAME PLACE.

ORE-CONCENTRATOR.

SPECIFICATION forming part of Letters Patent No. 435,530, dated September 2, 1890.

Application filed April 7, 1890. Serial No. 346,979. (No model.)

To all whom it may concern:

Be it known that I, JAMES TALLEY, a citizen of the United States, residing at Denver, in the county of Arapahoe and State of Colorado, have invented certain new and useful Improvements in Ore-Concentrators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in ore-concentrators of the class designed to separate the precious metals from the rock and gangue of pulverized, comminuted, or finely-crushed ores; and the object of my invention is to produce a machine which shall not only separate the mineral from the gangue, but which at the same time shall divide the concentrates into any desired number of grades corresponding with the different degrees of fineness to which the comminuted mineral is reduced. This I accomplish by the use of a series of tables arranged in steps one above the other and at a suitable inclination to the horizontal, the first or most elevated table of the series having for its object the usual functions of a concentrating-table—namely, the separation of the material therein into tailings and concentrates, the latter being the heavier and traveling gradually up the inclined plane of the table and over its edge to the table next below, while the tailings, being the lighter, work down the inclined plane of the table and over its lower edge to a chute, from which they may be carried to the lowest table of the series and there subjected to further treatment, if desired, or they may be discharged directly to the dump, as may be desired. All the tables of the series after the first or most elevated, therefore, have only concentrates to deal with, and their only function is the grading of the concentrates, the lighter or finer particles passing down the incline over the rear edge of the tables and into a suitable receptacle, while the coarser and heavier particles pass up the inclined plane of the table's surface and over

the head to the table next below, where said material is treated as before, and so on, a separate table being made for each grade of concentrates desired.

To this end my invention consists of the features, arrangements, and combinations hereinafter described and claimed.

In the drawings is illustrated an embodiment of my invention, in which—

Figure 1 is an elevation of one side of the complete machine. Fig. 2 is a similar view of the opposite side of the same. Fig. 3 is a front end view of the machine. Fig. 4 is a rear end view of the same. Fig. 5 is a top or plan view of the mixer. Fig. 6 is a section taken longitudinally through the center of the mixer. Fig. 7 is a detail view showing part of one of the lower arms of the mixer. Fig. 8 is a front view of one of the concentrating-tables. Fig. 9 is a side view or elevation of the same. Fig. 10 is a detail view showing the manner of pivoting the lower extremity of the upright supports of the table. Figs. 11, 12, 13, and 14 are detail views of a cam, showing also the connecting-rod or pitman, by means of which mechanism a reciprocating movement is imparted to each table of the series. The different figures show four positions of the pitman relatively to the parts of the cam. Fig. 15 is a front view in perspective of the distributor. Fig. 16 is a detail view of the shaft, pulley, and eccentric for giving the longitudinal movement to the distributor. Fig. 17 is an elevation of the screens, illustrating the mechanism by means of which the oscillating movement is imparted thereto. Fig. 18 is a top view illustrating the foraminous character of the screens and their different degrees of mesh in the order of their arrangement, the top screen being broken away to show the one beneath, which in turn is broken away to show the bottom one. Fig. 19 is an elevation, partially in section, illustrating the mechanism for imparting the longitudinal movement to the distributor.

In the views let the reference-numerals 1, 1, &c., designate four upright bars or standards forming the frame-work for the head or forward portion of the mechanism. These bars 2 are connected at the top by the cross-bars 2, &c. The lower extremities of the outer

bars 1 at the head of the machine rest upon the ground, the length of these bars being sufficient to raise the machine as far from the ground as necessary or desirable.

- 5 3 are side beams on each side of the frame, being suitably connected at the head of the machine with bars 1, and the opposite extremities to the short upright bars 4, forming the rear legs for the machine's support, bars 10 3 being also centrally supported by additional legs 5. These legs 4 and 5 are shown broken away in the drawings, yet they must be understood to rest upon the ground and form part of the support for the mechanism. From leg 4 15 the extension side bars 6 continue for a short distance to the tail of the machine. To the rear extremity of the bars 6 are connected the short upright bars 7, from the top of which the bars 8 extend toward the head of the machine and in a direction parallel with bars 6. From the inner extremity of bars 8 are erected the vertical or upright bars 9. From bars 3 on each side and toward the head of the machine extend the upright bars 10 to about 20 25 half the height of the beams 1 at the head of the machine. The upper extremities of the bars 10 are connected with the two beams 1, farther toward the rear of the machine, by means of the short horizontal bars 11. Bars 30 9 and 10 are connected on each side of the machine by the horizontal side bars 12. To the under side of the lowest side bars 12 are secured the short vertical bars 13, which make a right-angular turn toward the head of the 35 machine and merge into the horizontal bars 14, which are parallel with bars 12 and are connected at their forward extremity to the upright bars 10, as shown.

The entire frame-work of the machine as 40 constructed and as herein shown consists, preferably, of tubular bars, resembling the ordinary gas-pipe, of a size proportionate to the weight of the mechanism and the load to be supported thereon. By the employment of 45 this construction of frame I obtain the required strength for the purpose of the machine with a minimum weight of material.

It may be well to observe that while I have 50 described a suitable frame-work for my machine the arrangement and connection of tubular bars is only typical of any other similar arrangement or connection that might be employed.

Between the cross-bars 2 at the top of the 55 machine is suitably pivoted and suspended the rocking hopper 15, provided with two wedge-shaped compartments 16.

17 is the rocker-arm rigidly secured to the hopper at one extremity, its opposite or lower 60 extremity being pivotally secured to the connecting-rod 18, the opposite extremity of which rod is secured to the wrist 19 of the eccentric 20, the eccentric being made fast to the outer extremity of the shaft 21, suitably 65 journaled at 22 22 to the extension-bars 24, made fast at their inner extremities to two of the upright bars 1 of the main frame.

Shaft 21 is also provided with a pulley-wheel 23. This shaft is the motor-shaft of the machine, and to it power is applied by means of 70 a crank or in any other suitable manner for giving motion to all parts of the machine by virtue of the connection and arrangement of the mechanism, as hereinafter described.

Beneath the hopper 15 there is arranged a 75 series of screens 25, 26, and 27, each screen having the flanges or rims 120, the sides of which flanges are provided with small pulleys or rollers 28, which engage or rest upon tracks 29 as the screen moves back and forth under 80 the influence of suitable propelling mechanism. As shown in the drawings, each of these screens is connected by a rod J with an upright bar K, which is pivoted at its lower extremity to short horizontal bar L, as shown at 85 M. Each rod J is suitably pivoted at one extremity to upright bar K, as shown at N, and at its opposite extremity to one of the screens 25, 26, and 27, as shown at O. An oscillating movement is imparted to bar K and the screen 90 with which it is connected by an eccentric P, secured to shaft 21, the eccentric being connected with the bar K by a rod Q, having one extremity secured to the strap of the eccentric and the opposite extremities hinged or 95 pivoted to the bar K. These screens are arranged according to the fineness of their mesh, the coarser being the highest, and so on.

Each screen is provided at one end with a discharge 30, into which passes the coarse material which the spring rejects, this coarse material passing thence from the discharge-spouts to a chute 31, which carries it from the machine to the dump. The finer material which passes through the screens is finally 105 discharged into the stationary hopper 32, formed with two wedge-shaped discharge-spouts 33 33, from which the material passes through chute 135 to the mixer 34, which consists of circular compartments 35 35, communicating with each other by means of an aperture 36, formed in the lower portion of the adjoining partition-walls. Compartments 35 are inclosed in a single jacket 37, leaving a space 38 between the jacket and 115 the walls of the mixer. Space 38 forms a passage or channel through which heat is passed around the compartments of the mixer for the purpose of warming the material therein to any desired degree and maintaining the pulp at the proper temperature. Hot air or steam may be used for this purpose. The heating medium, as steam, passes into the chamber 38 through one extremity of a pipe 39, which is connected with any suitable 120 source of steam-supply, and out at the other extremity after having passed around the mixer. A pipe may be coiled around the mixer within space 38, forming a continuation of pipes 39 39, one of said pipes 39 forming 125 the inlet and the other the outlet for the steam or hot air. The pipe within the space may be coiled any desired number of times around the mixer. The two compartments 35

130

of the mixer are exactly alike in construction. Each has a conical bottom 40, with the apex in the center, the sides of the cone sloping gradually to the walls of the receptacle, as shown. In the center of each receptacle is a vertical shaft 41, having its lower extremity pointed and resting upon the apex of the bottom. The lower portion 42 of each shaft 41 is square at 42 and provided with a collar 43, of corresponding shape, sufficiently loose thereon to have a free vertical movement back and forth upon part 42 of the shaft.

To each collar 43 are rigidly secured the agitators 44, consisting of two radial arms 15 made fast to the collar at opposite points. To the outer extremity of each of these arms are adjustably secured the extensions 45, which telescope within arms 44, being provided with pins or lugs 46, which move back and forth 20 within slots 47 of the agitators. This construction allows the agitators to adjust themselves to the conditions of the material within the mixer by moving up and down upon the shaft or changing the length of their arms.

25 To the upper portion of each shaft 41 and near the top of receptacles 35 is another sleeve 48, rigidly secured upon the shaft and turning therewith. To each sleeve 48 is rigidly secured a pair of arms 49, the arms being located 30 on opposite sides of the sleeve, as shown.

To the top of each shaft 41, which extends considerably above the receptacles 35, is rigidly secured a pulley 50, one of said shafts being provided with an extra pulley 51, which 35 is connected with a pulley 52 upon motor-shaft 21 by means of a belt 53. By this means motion is communicated to one shaft 41 and from this latter shaft to the other similar shaft of the same name by means of a belt 40 54, which connects pulleys 50.

The material after reaching the mixer is supplied with sufficient water for its proper treatment, or the water may be added to or mingled with the material when it is first introduced to the hopper 15, if deemed desirable. The use of water being an ordinary expedient in the treatment of ores, it is not deemed essential to show any mechanism for this purpose. After thorough treatment with 45 in the mixer in the manner described the material passes thence through a suitable pipe or spout 55 to the distributer 56, which consists of a trough supported across the machine in front of the mixer and slightly below the same, so that the material passes from the one to the other by its own gravity. The distributer is supported by and pivoted to the suspension-rods 57, which are pivotally secured at their upper extremities to the horizontal bars 58, which are rigidly secured to two of the standards 1 and extend forward therefrom to a point directly above the distributer, so that rods 57 when at rest hang normally in a vertical position. The distributer obtains a lateral or transverse movement from an eccentric 59, secured to a bar 60, suitably journaled at 61 and 62 to the standards

1 and 9, respectively. Rigidly secured to bar 60 near its upper extremity is the small pulley 63, having a groove in its periphery and 70 connected with a smaller pulley 64 on motor-shaft 21 by means of a suitable belt 65. Motion is communicated from shaft 21 to shaft 60 by means of the belt 65 and the pulleys which it connects.

66 is a connecting-rod, one extremity of which is suitably secured to the strap of the eccentric 59, the other extremity of said rod being hinged or pivoted to the adjacent suspension-bar 57. This mechanism gives the 80 lateral movement to the distributer when power is applied to the shaft 21, or a longitudinal movement or a movement at right angles to the lateral movement just described may be imparted to the distributer. This is 85 accomplished by means of connecting-rod A, suitably hinged at one extremity to the distributer, the opposite extremity being secured to the strap of an eccentric B, rigidly secured to a shaft C, journaled in suitable boxes D, 90 made fast to two of the bars 1 of the framework.

E is a pulley mounted upon shaft C and connected by means of a belt H with another pulley F, mounted upon shaft 103. Power is 95 communicated to shaft 103 in the manner hereinafter described, and thence to the distributer by virtue of the mechanism just described.

Pipes 157 carry off the surplus water from 100 the distributer.

The function of the distributer is suggested in its name, and consists in distributing the material received from the mixer evenly upon the first table of the series heretofore mentioned.

67 is an inclined plate or chute conducting the material from the distributer to the first table. The passage of this material from the distributer is regulated by means of a 110 slide 68, operated by a lever 69, a ratchet 70, and suitable connecting-bars 71, 72, and 73. Hence at the will of the operator the material passes from the distributer to the first or most elevated table of the series, which tables I will designate by the numerals 74, 75, 76, 77, and 78, in the order of their elevation, beginning with the highest. These tables are all of similar or identical contour and supported and operated in the same manner. 115 In Figs. 8 and 9 are shown, on an enlarged scale, a front view and a side view, respectively, of one of these tables.

The upper portion of each table or the table proper consists of a plate composed of 125 metal or other suitable material, having its surface divided longitudinally or divided on the line of the machine's length by the parallel strips 178. The forward extremity of each table is provided with a spirit-level 79, 130 for use in controlling and adjusting this portion of the table, which should at all times be maintained in a horizontal position.

Each table is supported on four pins or

legs 80, suitably hinged or pivoted to the under side of the machine at one extremity and at the opposite extremity seated in sockets 81, formed in the top of suitable supports 82, 5 made fast to the transverse side bars 83, seated upon and made fast to the side bars of the frame, which engage the recesses 84, formed in the lower edges of bars 83.

Each table is provided with two springs 85 10 and 86. Spring 85 occupies, normally, a vertical position, and is made fast at one extremity to the under side of the table proper and at the opposite extremity to suitable stationary bars 87 below. Spring 86 occupies a 15 sort of diagonal position, being secured at one end to the under side of the table near its forward extremity and at the opposite end to the stationary bars 83 below and near the rear extremity of the table. The springs tend 20 to keep the table normally in the upright position.

88 88, &c., are water-pipes extending across the machine above the tables, which they supply with water sufficient for the treatment of 25 the material thereon. The water passes from the main pipes through the smaller pipes 89, which are supplied with faucets 90 for regulating the supply. Pipes 88 are supported upon suitable standards 191.

30 Each table is provided with bumpers R, rigidly secured to the stationary transverse bar 83. A metal plate S, secured to the under side of the movable top portions of the table, engages the bumper R during the movement 35 of the table, as hereinafter described. Each of these tables is given a reciprocating movement through the medium of a pitman 91, suitably pivoted at one extremity to each side of the table, as shown at 92, the opposite 40 extremity of each pitman being connected with a cam 93 of peculiar construction. Each of these cams consists of a disk 94, an arm 95, and a pin or lug 96. These disks are rigidly secured to the opposite extremities of 45 shafts 97, which extend transversely across the front of the machine, being suitably journaled to and supported by two of the vertical bars 1 of the frame-work. To each disk is pivoted, at a point 98 outside of its center, 50 the short arm 95, to which arm is pivotally secured at 99 the forward extremity of a pitman 91, said pitman point of attachment being far enough from the pivotal point of the arm to give the desired length of stroke to 55 the pitman.

The shafts 97 are arranged on a vertical line, one above the other, and correspond in number with the tables to be operated. Each of these shafts is provided with a pulley 100, 60 rigidly secured thereto. Each pulley 100 is connected with a pulley 101, rigidly secured to a shaft 103, suitably journaled to the outer vertical bars 1, forming part of the frame-work of the machine heretofore described. Shaft 65 102 has a pulley 101 for each pulley 100 on shafts 97. Hence each pulley 100 on a shaft 97 is connected with a corresponding pulley

101 on shaft 103 by means of a suitable belt 104.

Rigidly secured to one extremity of shaft 70 103 is the bevel gear-wheel 105, meshing within a similar wheel 106, secured to one extremity of a shaft 107, journaled at 108 to the vertical bars 1 of the frame-work. Shaft 107 is provided with a pulley 109, rigidly secured thereto. Pulley 109 is connected with pulley 23 on the motor-shaft 21 by means of a belt 110. It will be seen that motion is communicated from shaft 21 to shafts 97, whose movement gives the tables the desired reciprocating 80 movement by virtue of the pitman-rods extending from the tables to the cams 93. The action of these cams will be better understood by reference to Figs. 11, 12, 13, and 14.

In describing the operation of the cam I 85 will suppose that the parts are in the relative positions shown in Fig. 11, the tables having just sprung forward, under the influence of the spring-rods 85 and 86, to their forward limit of motion, engaging the bumpers R and 90 giving the tables that sudden jar incident to such actions. When the disk 94 has made about one-half of another revolution, the pin 96 has traveled from the position shown in Fig. 11 to that shown in Fig. 12, where it engages the arm 95, which engagement continues until the arm again springs from the pin to the position shown in Fig. 11, the parts occupying in the meantime a variety of positions, two of which only are illustrated— 100 namely, those shown in Figs. 13 and 14. In Fig. 13 the parts are shown just before the pitman is drawn backward to its extreme limit, while in Fig. 14 the parts are shown in their relative positions when the pitman has 105 reached its limit of backward movement, being the position directly opposite that shown in Fig. 11, the arm and the pitman in both cases lying parallel or in a direct line with each other. The least movement from the position shown in Fig. 14 in the direction indicated by the arrows throws the pitman and arm out of line with each other or destroys their parallelism, and the arm and the pitman immediately spring again away from 115 the pin 96 to the position shown in Fig. 11, being actuated by the spring-rods 85 and 86, connected with the tables. This action of the tables affects the material thereon in the manner heretofore described. The first or more elevated table 74 separates the material thereon into concentrates and tailings, the former passing over the more elevated front portion of the table to the table 75 next below, while the tailings pass to the transversely-inclined 125 spout 111 to the longitudinally-inclined spout 112 or to the dump, as may be required. If it is deemed necessary to re-treat the tailings, they are carried by chute 112 to a suitable distributor 113, and thence through the spout 130 114 to the last table 78, where the material is subjected to the same treatment that it originally received on the first table. Distributor 113 is operated in a manner similar

to the distributor 56, whose operation has been heretofore described. Distributer 113 is supported by rods 116, pivoted at their upper extremities to cross-bar 117, connecting the vertical bars 99. The lower extremities of rods 116 are hinged to the distributor 113.

Secured to the inclined side of bar 60, heretofore described, is an eccentric 177, to the strap of which is secured one extremity of the connecting-rod 118, the opposite extremity of this rod being suitably hinged to the distributor. Hence as soon as bar 60 is set in motion a lateral movement is given this distributor, the same as a similar movement to distributor 56. 15 When it is not desired to re-treat the tailings from the first table, they are of course carried to the dump, and in this case table 78 is elevated sufficiently to form one of the series of tables and collect the mineral passing from 20 the higher extremity of table 77 next above.

The grading of the concentrates upon the remaining tables 75, 76, and 77 of the series has already been referred to. The grade from each table passes over the table into a 25 suitable inclined chute 115 and thence into a suitable receptacle, or it may pass directly from the table to the receptacle.

From the description heretofore given it is believed that the operation of the machine 30 will be fully understood, since the function of each part has been mentioned in connection with the description of its construction.

Having thus described my invention, what I claim is—

35 1. In an ore-concentrator, a mixer for rendering the comminuted material a homogeneous mass, said mixture being suitably located for receiving the material to be treated therein, and consisting of two contiguous circular compartments 35, having an opening 36 leading from one to the other, a vertical shaft 41, provided with radial arms, said shaft being suitably located and supported in the center of each compartment, and means for rotating 45 said shafts, substantially as described.

2. In an ore-concentrator, a mixer for rendering the material discharged therein a homogeneous mass, and consisting of one or more circular compartments 35 and a vertical shaft 41, centrally located in each compartment and provided with radial arms secured to a collar surrounding the lower portions of the shaft and having a free vertical movement but no rotary movement therein and turning 55 freely therewith, substantially as described.

3. In an ore-concentrator, a mixer for rendering the material discharged therein a homogeneous mass, said mixer consisting of one or more circular compartments having a 60 rotating shaft centrally located therein and provided with radial arms automatically adjustable longitudinally, substantially as described.

4. In an ore-concentrator, a mixer for rendering the material discharged therein a homogeneous mass, and consisting of one or more circular compartments 35, each having a ver-

tical rotating shaft centrally located therein and provided with two sets of radial arms, one upon the upper portion, rigidly secured 70 thereto, and the other upon the lower portion, having a free vertical movement thereon, substantially as described.

5. In an ore-concentrator, a series of inclined reciprocating tables arranged in steps 75 one above the other, each table being supported upon legs 80, the upper extremities of which are pivoted to the under side of the table and their lower extremities seated in sockets formed in blocks 82, secured to a stationary supporting-frame, each table also being provided with spring-rods 85 and 86, the former occupying a vertical and the latter an oblique position, one extremity of each rod being made fast to the under side of the table 85 and the opposite extremity to the stationary frame-work underneath, suitable bumpers, and means of simultaneously imparting to each table of the series a reciprocating movement, substantially as described. 90

6. In an ore-concentrator, an inclined reciprocating table supported upon legs 80, their upper extremities being pivoted to the under side of the table and their lower extremities seated in sockets formed in blocks 82, secured 95 to a stationary supporting-frame, spring-rods 85 and 86, the former occupying a vertical and the latter an oblique position, one extremity of each rod being made fast to the under side of the table and the opposite extremity to the stationary frame-work underneath, bumpers R, secured to the stationary support underneath the table and normally engaging a plate on the under side of the table, and means of alternately drawing the 105 table from the bumpers and releasing the same to suddenly and forcibly re-engage the bumpers under the influence of the spring-rods, substantially as described.

7. In an ore-concentrator, a suitable table 110 supported upon legs permitting a free forward and backward movement and mechanism for imparting to the tables a reciprocating movement, said mechanism consisting of a pitman-rod having one extremity pivoted 115 to the table and the opposite extremity connected with a cam consisting of a disk, an arm, and a pin, the disk being made fast to the extremity of a rotating shaft, the arm pivotally secured to the disk outside of the 120 center, a pitman pivoted to a wrist upon the cam, and the pin being located outside of the center of the disk and adapted to engage the arm as the disk revolves with the shaft and draw the table forward to a certain point, 125 when the arm is released from the pin and the table springs backward under the influence of suitable spring-actuating mechanism to sudden and forcible contact with the bumpers, substantially as described. 130

8. In an ore-concentrator, a cam for imparting a reciprocating movement to the tables, said cam consisting of a disk 93, rigidly secured to the extremity of a rotating shaft, an

arm 95, pivotally secured to the disk outside of the center and provided with a wrist, to which one extremity of the pitman is pivoted, a pin or lug 96, rigidly secured to the disk outside of the center and at a suitable distance from the pivotal point of the arm, the pin being adapted to engage the arm and carry it around to a certain point, when the arm is released from the pin and springs back-

ward with the pitman under the influence of 10 suitable actuating mechanism connected with the table, substantially as described.

In testimony whereof I affix my signature in presence of two witnesses.

JAMES TALLEY.
